UNITED STATES PATENT OFFICE.

WILLIAM J. MCLOONEY AND EDITH B. PRESTON, OF MEXICO, MISSOURI.

HOUSEHOLD-SIFTER.

No. 874,109.

Specification of Letters Patent.

Patented Dec. 17, 1907.

Application filed March 23, 1907, Serial No. 364,073.

To all whom it may concern:

Be it known that we, WILLIAM J. MCLOONEY and EDITH B. PRESTON, citizens of the United States, residing at Mexico, in the county of Audrain and State of Missouri, have invented certain new and useful Improvements in Household-Sifters, of which the following is a specification.

The present invention relates to certain new and useful improvements in the construction of sifters and screens, and more particularly to that type of sifters which are especially designed for household use, the primary object being to provide a sifter of this character by means of which flour or similar material can be quickly and thoroughly reduced to a powdered state.

Broadly speaking the sifter embodied by the present invention is in the nature of a tubular body portion comprising a series of annular sections, each section carrying a sifting screen and means being provided whereby the various sifting screens can be caused to oscillate in unison so that as the flour falls through the body portion it is thoroughly agitated and caused to pass through the various screens in such a manner as to thoroughly remove all the lumps.

For a full description of the invention and the merits thereof and also to acquire a knowledge of the details of construction and the means for effecting the result, reference is to be had to the following description and accompanying drawings, in which:

Figure 1 is a side elevation of a sifter constructed in accordance with the present invention. Fig. 2 is a transverse sectional view on the line 2—2 of Fig. 1. Fig. 3 is a longitudinal sectional view through the sifter. Fig. 4 is a detail view showing the method of attaching the lower end of the handle to the lower section of the sifter.

Corresponding and like parts are referred to in the following description and indicated in all the views of the drawings by the same reference characters.

The numeral 1 designates the lower section of the tubular body portion, and this section is shown as provided with the supporting legs 2 by means of which the sifter is normally held in a spaced position with respect to the support upon which it rests. The upper section 3 of the tubular body portion has the handle 4 rigidly connected thereto, the lower extremity of the handle being provided with the extensions or prongs

5 which fit removably within a suitable keeper 6 upon the lower section 1. Interposed between the lower section 1 and the upper section 3 of the tubular body are a series of intermediate sections 7, in the present instance two in number. The lower edge of the upper section 3 and each of the intermediate sections 7 is drawn inwardly preferably by crimping as indicated at 8 and the said crimped portion fits within the upper edge of the next lower section when the various sections are assembled in position for use as shown in Fig. 1.

Immediately above the crimped portion 8 of each of the intermediate sections 7 and the upper section 3 there is located an outwardly pressed annular rib 9 which forms a shoulder engaging the upper edge of the next lower section and constituting a stop to positively limit the telescoping action of the crimped portions 8. Each of the annular sections of the tubular body portion is also provided with an inwardly pressed annular rib 10 which constitutes a seat upon which the sifting screens normally rest.

In the specific construction of the sifting screens it will be observed that the same comprise rings 11 fitting loosely within the various sections of the tubular body and having their lower edges connected by netting or screen 12, the said rings 11 being supported by the ribs 10 in such a manner as to have an oscillatory movement thereon. A laterally extending arm 13 is carried by each of the rings 11, the said arms passing outwardly through slots 14 formed in the tubular body portion and being designed to move longitudinally of the slots to impart oscillatory movement to the sifting screens. The outer extremity of each of the lateral arms 13 is formed with an eye 15 and the various arms are connected by a rod 16 extending through the said eyes. It will thus be apparent that by moving the rod 16 back and forth so that the arms 13 play within the slots 14 the various sifting screens 12 can be given a simultaneous oscillating movement. It may be found desirable as in the present instance to mount a series of sleeves 17 upon the rod 16 in order to provide a suitable operating handle.

In order to hold the various sections of the tubular body in operative position, a pair of locking members 18 are employed, the said locking members having their lower ends pivotally connected to the lower section 1, while their upper ends are formed with hook

portions which are designed to engage with the upper edge of the top section 3 of the tubular body.

Should it be desired to dismount the sifter it is simply necessary to swing the locking members 18 out of engagement with the upper section 3 and remove the rod 16. The various sections can then be lifted out of engagement with each other, and the sifting screens removed from their respective sections by first tilting the same and then moving the same laterally over the upper edge of the section until the arm 13 has been disengaged from the slot 14.

15 Having thus described the invention, what is claimed as new is:

1. In a device of the character described, the combination of a tubular body comprising a series of annular sections, the lower edge 20 of each section being crimped and received within the upper portion of the adjacent section, each of the sections having a rib pressed outwardly therefrom to form a stop for limiting the telescopic movement of the sections 25 and also having an annular seat pressed inwardly therefrom, a sifting screen carried by each of the sections and resting loosely upon the seat, and means for imparting movement to the sifting screens.
- 30 2. In a device of the character described, the combination of a tubular body portion provided with a series of annular seats and also with a series of slots, a sifting screen supported by each of the annular seats, a lateral 35 arm carried by each of the sifting screens and operating within one of the slots, and a handle member connecting the lateral arms

whereby the sifting screens can be moved in unison.

3. In a device of the character described, 40 the combination of a tubular body portion comprising a series of annular sections, each of the sections being formed with a seat and also with a slot, a sifting screen carried by each of the sections and resting upon the 45 seat, and an arm projecting from each of the sifting screens and passing through the respective slot in the annular section, the said arms being provided with eyes, and a rod connecting the arms and passing through the 50 eyes thereof.

4. In a device of the character described, the combination of a tubular body portion comprising a series of annular sections, a sifting screen carried by each of the sections, a 55 handle connected to one of the sections and provided with an extension, and a keeper carried by one of the sections for receiving the said extension upon the handle.

5. A household sifter comprising a series 60 of superposed annular sections, a sifting screen loosely mounted within each of the sections, connecting means between the end sections, and a handle permanently connected to one of the end sections and detachably engaging the opposite end section.

In testimony whereof we affix our signature in presence of two witnesses.

WILLIAM J. McLONEY. [L. S.]
